(57) **CLAIM**

We claim the ornamental design for a solar powered speaker, as shown and described.

DESCRIPTION

FIG. 1 is a top, front perspective view of a solar powered speaker, showing our new design in a closed position;

FIG. 2 is a bottom, rear perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof;

FIG. 8 is a left side view thereof;

FIG. 9 is a top, front perspective view thereof, shown in an open position;

FIG. 10 is a bottom, rear perspective view of FIG. 9;

FIG. 11 is a top view of FIG. 9;

FIG. 12 is a bottom view of FIG. 9;

FIG. 13 is a front view of FIG. 9;

FIG. 14 is a rear view of FIG. 9;

FIG. 15 is a right side view of FIG. 9; and,

FIG. 16 is a left side view of FIG. 9.

The unequal length (i.e. dash-dot) broken lines represent the bounds of the claimed design while all other broken lines are included for the purpose of illustrating portions of the solar powered speaker; the broken lines form no part of the claimed design.

The solar powered speaker is shown with symbolic breaks in its length and width in all drawing views. It is understood that patentability is based only on those portions of the article that are shown in solid lines, and the appearance of any portion of the article between the break lines forms no part of the claimed design.
